UNITED STATES PATENT OFFICE.

LYCORTES D. MERRICK, OF NEW YORK, N. Y.

AERIAL VESSEL.

No. 856,895.

Specification of Letters Patent.

Patented June 11, 1907.

Application filed May 23, 1906. Serial No. 318,335.

To all whom it may concern:

Be it known that I, LYCORTES D. MERRICK, a citizen of the United States, and a resident of the city of New York, borough of Manhattan, in the county and State of New York, have invented a new and Improved Aerial Vessel, of which the following is a full, clear, and exact description.

My invention relates to an improvement in aerial vessels, and one of the purposes of the invention is to combine in one vessel the aeroplane and balloon systems in such manner that the two systems will co-operate and be under the complete control of the operator, and so that the frame of the vessel may be made of exceedingly light material, timber for example, and yet be safe and strong and capable of all the elasticity necessary for a vessel of its character.

20 A further purpose of the invention is to construct a skeleton frame which bears a striking resemblance to the hull of a vessel, having a keel and outwardly-extending swelling sides, departing only from such resemblance in that the construction of the framework at the bow is nearly duplicated at the stern, and the bow is provided with means for supporting the vessel in its flight and the stern is provided with a small aeroplane 25 acting in conjunction with the rudder or steering apparatus, which latter is so constructed that when making a sharp turn, or when flying in a small circle the vessel will not cant to any appreciable extent but will 30 maintain practically an even keel.

Another purpose of the invention is to provide simple, effective and strongly-braced paddle wheels so arranged as to equalize the weight and produce a uniform 35 motion when in operation, since all of said wheels are driven from a single motor having a central location in the keel section of the vessel.

It is also a purpose of the invention to 40 so arrange the said paddle wheels that under all conditions they will be accessible to all the available air, said paddle wheels being mounted to operate in hoods having a maximum air-receiving capacity, which paddle 45 wheels operate in conjunction with adjacent and rearwardly positioned sustaining devices, the air in the hoods being somewhat under compression for a given length of time.

A further purpose of the invention is to 50 provide an arrangement of sustainers and hoods, which serve as so many balloons to

assist in raising and sustaining a vessel while the paddle wheels act directly to effect its propulsion.

It is also a purpose of the invention to provide a construction of rudder that may be utilized as a brake when necessary.

The invention consists in the novel construction and combination of the several parts, as will be hereinafter fully set forth and pointed out in the claims.

Reference is to be had to the accompanying drawings forming a part of this specification, in which similar characters of reference indicate corresponding parts in all the figures.

Figure 1 is a side elevation of the vessel; Fig. 2 is a plan view of the same; Fig. 3 is a central longitudinal section through the entire vessel; Fig. 4 is an enlarged vertical transverse section through a portion of the frame and one of the paddle wheels and its hood; Fig. 5 is a section taken practically on the line 5—5 of Fig. 4; Fig. 6 is an enlarged horizontal section through the frame of the machine, taken below the sustainers and paddles and practically on the line 6—6 of Fig. 1; Fig. 7 is an enlarged vertical section through a portion of the frame of the vessel at the stern, showing the main rudder in side elevation and the auxiliary or brake rudder in section; Fig. 8 is a transverse section through the vessel, drawn upon an enlarged scale, the said section being taken practically on the lines 8—8 in Figs. 1 and 3; Fig. 9 is a vertical section taken substantially on the line 9—9 of Fig. 1; Fig. 10 is a vertical section taken practically on the line 10—10 of Fig. 1; Fig. 11 is an enlarged vertical longitudinal central section through a part of an end of the frame, showing the manner in which the members of the frame are connected; Fig. 12 is a vertical transverse section taken practically on the line 12—12 of Fig. 11; Fig. 13 is a longitudinal section through the weight-carrying block employed in connection with the frame of the machine and located at the bow; Fig. 14 is a diagrammatic view of the frame, illustrating the manner in which the various paddles may be driven from the motor employed; and Fig. 15 is a diagrammatic view of the bottom portion of the vessel looking upward, and illustrating the various positions of the lower series of aeroplanes.

Preliminary to a detail description of the construction of the improved air ship, I desire to state generally that the ship is so constructed as to permit the use of numerous

paddle wheels more or less triangular in shape, which beat the air similarly to the wings of a bird, with this advantage, the bird has but two wings of a particular description and the air ship has been arranged for a number of paddle wheels B, each having three concaved or scoop-shaped blades or beating surfaces b, which press downward upon the air for about one-quarter of a revolution, lifting the air ship, and then pass backward one-quarter of a revolution, thereby pulling the vessel forward; then the blades b pass under segmental hoods B', to prevent back-windage, for nearly one-half of a revolution, and finally the blades b emerge from the hood B' and repeat the work of lifting and propelling the vessel. The aforesaid paddle wheels are distributed in the frame A of the vessel in such manner as to establish the stability or equilibrium of the vessel, by grouping the paddle wheels in a maximum number at each end portion of the vessel and locating a minimum number of paddle wheels amidship, which not only upholds the vessel but by means of the arrangement of the beating or paddle wheel blades along the outer side of the vessel, stability athwart-ship is obtained.

In the present construction the paddle wheels are eight in number, three being placed at each side of the upper central portion of the frame A, and one in front and the other at the rear of the said upper central portion of the frame.

In connection with the paddle wheels B and their hoods B' I employ sustaining devices C, and each of said devices comprises a more or less diamond-shaped hollow body fully open at the front and at the rear, an upper aeroplane 10 and a lower aeroplane 11; but in the construction of the central sustaining devices designated as C' the aeroplanes are omitted. The sustaining devices C receive and temporarily retain the distributed whirling and eddying air which the side paddle wheels produce, while the central sustaining devices C' receive and temporarily retain the air distributed by the end paddle wheels B. The sustaining devices or sustainers C and C' utilize the combined currents of air by holding or compressing the air between their members and converting these mixed currents of air into a lifting and sustaining power, performing the same functions with more direct effect than the air or gas bags of the average air ship. It may be here stated, however, that in addition to the aforesaid sustainers one or more gas bags or envelops may be applied to the upper portion of the frame of the vessel if deemed desirable.

The sustaining devices C and C' are arranged at definite points in the frame A, as has been stated, and wherever practical they are abaft the next paddle wheel B, so that they will unfailingly catch and compress the

whirling currents of air thrown backward by the motion of the said wheels and rearrange the air into more or less straight and steady currents for the succeeding wheels to grasp and in their turn throw back into their sustainers. The sustainers and paddle wheels will be hereinafter described in detail.

The frame A is constructed of light material, preferably thin yet strong strips of wood being employed; and in the construction of the frame the strips overlie one on the other wherever it is possible or they cross each other, the engaging strips being secured together by means of light bolts or equivalent fastening means. In general construction the frame may be said to comprise a lower or keel section a, in which the passengers are accommodated and the operative mechanism is located, and an upper or body section a', which is wider than the keel section a, the latter section extending down from the longitudinal central portion of the body section a', together with a bow section a² and a stern section a³. These bow and stern sections are practically continuations of the central end portions of the body section at the top.

In the detail construction of the framing of the vessel and as illustrated, it consists of longitudinal, parallel, upper strips 12 and 12^a located at each side of the center, and upper outer side strips 13 and 13^a parallel with the central strips 12 and 12^a, which latter strips extend some distance forward or rearward of the side strips 13 and 13^a as best shown in Fig. 14.

Parallel and vertically alineing, longitudinal central strips 14 and 14^a are provided below the upper central strips 12 and 12^a, being removed a desired distance therefrom; and in the further construction of the body of the frame, or its upper portion a', lower side strips 15 and 15^a are provided, parallel with and beneath the upper side strips 13 and 13^a as best shown in Fig. 8. Vertical central strips 16 and 16^a are secured in any suitable or approved manner to the longitudinal horizontal strips 12 and 12^a, 14 and 14^a, as also shown in Fig. 8, and the vertical strips 16 and 16^a which are at the central portion of the body section a', are carried downward and constitute a portion of the framework of the keel section a, but the vertical strips 16 and 16^a which are at the forward and aft ends of the frame extend but a slight distance, if any, below the lower horizontal longitudinal members of the frame. The side strips 13 and 15, 13^a and 15^a are connected by vertical strips 17 and 17^a, as is also best shown in Fig. 8; and at the lower ends of the longer central vertical strips 16 and 16^a of the frame, rollers 18 are mounted to turn, whereby the vessel may be readily drawn along a solid surface. Transverse horizontal strips 19 are located at the upper portion of the frame, serving to tie together and brace the upper por-

tion of the vertical strips 17 and 17^a and the upper horizontal longitudinal strips 13 and 13^a, and corresponding lower transverse horizontal strips 20 are provided, which serve to tie together and brace the lower portions of the strips 17 and 17^a, the lower longitudinal horizontal strips 14 and 14^a and the central vertical strips 16 and 16^a. The upper transverse strips 19 serve to connect the central standards or strips 16 and 16^a with the longitudinal central strips 12 and 12^a, as is also shown in Fig. 8. At the forward and rear ends of the said upper section a' of the frame, upper and lower diagonal strips 21 and 21^a extend from the forward and rear uprights 16 and 16^a at the central portion of the said section a' to the forward and rear uprights 17 and 17^a at the side portion of the frame, as is also best shown in Fig. 14 but which is also indicated in Figs. 1 and 2. At the upper portion of the frame cross bars or strips 22 are provided, extending from the central longitudinal strip 12 to the opposing corresponding strip 12^a, meeting the inner end portions of the diagonal strips 21 at the said upper portion of the body as is clearly shown in Figs. 2 and 14. Thus it will be observed that the body portion a' of the frame is divided into a series of skeleton cubical sections D, and these sections are in three series, two outer series and a central series as is shown in Figs. 2 and 14, and the said body is likewise provided at each side of each end portion with a triangular skeleton section D' and at each extreme end with a skeleton rectangular portion D².

Diagonal braces 23 extend down from the outer or side strips 15 and 15^a and the lower transverse tie strips 20 to an engagement with and attachment to side strips 24 and 25, which constitute, in connection with the lower portions of the central standards 16 and 16^a, the structure of the keel section a; and a platform 26 is suitably erected upon cross bars 27, which connect the said lower portions of the standards 16 and 16^a as is shown in Fig. 8. The forward and rear standards 16 and 16^a are likewise connected and braced by cross bars 28 located above the cross bars 27 constituting the sills for the platform 26. The lower cross bars 27 are shown as attached to or connected with the lower side strips 25, and the upper cross bars 28 are shown as connected with the upper side bars or strips 24 of the said keel section a. I desire it to be understood, however, that I do not confine myself to the details of construction of the frame as set forth except in as much as the various sections D, D' and D² are necessary, and that a keel section should be provided in connection with the body section.

In the arrangement of the paddle wheels B and their hoods B', a paddle wheel and its hood are located in each end skeleton cubical

section D, and in the next section thereto at each side a sustainer C is located; and the same arrangement follows throughout the cubical sections D at the side portions of the body of the frame. A paddle wheel and its hood are also located in each central end cubical section D of the structure of the body as is shown in Fig. 2, the remaining skeleton cubical sections being each provided with a sustainer C', as is also best shown in Fig. 2, but which is also illustrated in Fig. 3. The forward frame section D² is supported by braces 29, which extend down to the keel section a, and similar braces 30 are provided for the rear frame section.

I employ a wedge-shaped aeroplane 31 at the bow of the vessel, which performs the same functions as the sustainers C and C', since it catches and holds the wedge of air beneath it, which air has a tendency to force the bow upward. The aeroplane 31 is made of fabric, or thin light metal, or other suitable pliable material, and is stretched over a ridge strip 32, extending from the central portion of the forward upper cross bar 19 to the next inner corresponding cross bar, as is best shown in Fig. 2. The outer edges of the said aeroplane are secured to the bow braces 29. A second aeroplane 33 is located at the stern of the vessel, serving to stand out at such point but to a lesser degree than does the bow aeroplane 31, the general effect being that of having the stern of the vessel a trifle lower than the bow, giving the vessel in action a similar position to that of a screw steam ship when properly loaded, wherein a certain amount of drag is obtained for the screw to act on the water, and to that end the stern aeroplane 33 is flat. It may thus be observed that since the bow points higher than the stern the paddle wheels B may each take hold of a fresh, unused, unbeaten quantity of air. This rear aeroplane 33 is suitably secured to the central strips 12 and 12^a and the rearmost and next inner bar 19.

With reference to the detail construction of the paddles B and their immediately associate factors, transverse or cross bars 34 are made to extend from side to side of the upper section a' of the vessel about midway between the sections D and D', being secured to the upright or standard strips with which they engage in any suitable or approved manner; and longitudinal beams or strips are likewise provided, crossing each of the aforesaid sections D and D' at each side of the sections, the outer bars or strips just mentioned and the transverse bars or strips 34 above referred to being located at about the central portions of the said sections D and D' and between the longitudinal main strips 13, 13^a, 15, 15^a, 12, 12^a and 14 and 14^a as is best shown in Figs. 1, 3 and 8. The transverse strips 34 are located about centrally between the upper transverse main strips 19 and the

lower main strips 20, as is shown best in Fig. 8. The longitudinal intermediate strips are in sections, namely, a single member 35 intervenes between parallel and spaced members 35^a, as is best shown in Figs. 1 and 3, the spaced members 35^a occurring wherever a sustainer C or C' is to be located in a section D or D' of the body.

The hood B' for a paddle wheel B is located in the section designed for it, and consists of end arches 36 and one or more intermediate arches 37, which extend from one transverse intermediate bar 34 to the other as is best shown in Fig. 4, and a covering 37^a, preferably of a strong fabric is secured to the said arches, to one of the cross bars 34 and to the members 35 or 35^a of the longitudinal intermediate bars, whichever member may be located at the section in which the paddle wheel is to be placed. The hoods B' are therefore segmental in cross section, and each hood at its forward bottom portion is provided with an opening 38 extending practically from end to end as the hood is closed at its ends, through which opening air is freely admitted as the vessel advances. The paddle wheel B, as is best shown in Fig. 4, consists of a triangular hub 39 which is secured upon a shaft 40, and said shaft 40 is made to turn in bearings 41 properly secured to the intermediate side strips crossing the said sections D and D' as is best shown in Fig. 9.

The blades b are three in number, one of the said blades being provided for each face of the triangular hub 39, and each blade consists of end members 42, which members extend outward flush with one of the faces of the hub 39, being connected by a bow member 43, and a bow 44 connects the end members 42 at points near their bow members. A body section 45 consisting of a stout fabric or the equivalent thereof is secured to the bow portions 43 and 44 and to the side members 42, and also to the hub 40 in any approved manner, so that the said plates are dished or scoop shaped, being practically triangular in cross section as is shown clearly in Fig. 4. The entire paddle wheel is strengthened by means of wire ties 46, which pass entirely around the wheel, being twisted around the bow portions of the blades, and the ends of the ties are then suitably connected.

The body portions of the blades b, of the paddles B, the covering for the hoods B' and the sustainers C and C', are made of canvas, rubber, silk, or a combination of different pliable materials, or of very light metals such as aluminium, since it is necessary that the material employed shall be as light as possible consistent with strength.

At the upper and lower central portions of each body section D and D' in which a sustainer is located, a longitudinal ridge pole or strip 47 is firmly secured to adjacent members of the frame; and the fabric body of a

sustainer is stretched more or less tightly over the upper and lower ridge poles or strips 47, and the twin members 35^a of the auxiliary or intermediate longitudinal strips on the frame, as is shown particularly in Figs. 1, 3 and 8. The sustainers are therefore diamond-shaped in general contour, being fully open at the front and at the back so as to receive the air forced thereto by an adjacent advanced paddle wheel, and to direct the air to the next succeeding paddle wheel.

Each sustainer C is made in two sections 48 and 48^a of equal size, and each section is secured in a firm manner to a corresponding member 35^a of the said intermediate side strips of the frame as best shown in Fig. 8, so that air will fully enter the sustainers through the openings 49 between the frame members 35^a. In order that the air may also freely enter the sustainers from the sides of the frame sections in which they are placed, and from the top and the bottom, their side edges are inwardly tapered from the ridge supports 47 to their point of attachment to the frame members 35^a as shown in Figs. 1 and 3, being narrower at such points. Beneath each sustainer C a substantially flat horizontal aeroplane 50 is secured to the frame, and an upper aeroplane 51 is likewise provided for each sustainer C, which latter aeroplanes extend over the top of the frame from one side to the other; the end portions 52 of the extended transverse aeroplanes are carried down at the sides of the upper sections of the frame and are secured to outriggers 53, forming a portion of the frame as particularly shown in Fig. 8. Thus it will be observed that all the air, from whatever source it may come, entering the section in which the sustainer is located, is directed thereto and utilized thereby.

The sustainers C' are like in construction to the sustainers C, and may or may not have their side portions open, and the upper aeroplanes are omitted but lower aeroplanes 54 are provided. The various sustainers C and C' are in the same horizontal plane with each other and with the paddle wheels and their hoods; and empty sections D are provided at the central portions of the body a' of the frame, which latter sections are more or less covered at the top by the upper aeroplanes 51 as indicated in Fig. 2. These empty sections in the frame occur between the sustainers C' and promote the proper circulation of air to and from the sustainers and the paddle wheels. The ridge poles 47 for the standards C' are secured in suitable bearings 55, as shown in Figs. 11 and 12, and corresponding bearings are provided for the ridge poles 47 for the standards C.

In addition to the aeroplanes above described, two front and two rear triangular aeroplanes designated as 56 and 57 are located at each side of the body section a' of the

frame at each end, the said aeroplanes being secured to the forward and rear diagonal side frame members 21 and 21^a, and to the inner longitudinal central frame members 5 12, 12^a, 14 and 14^a, as is best shown in Fig. 2. All of the paddle wheels B are driven from one motor 59, and this motor is located on the platform 27 at about the central portion of the keel section a' of the frame. A chain belt 60 is shown carried from the driving pulley of this motor 59 to a line shaft 62, which is supported in suitable bearings beneath the body portion a' of the frame, as is shown in Figs. 3 and 8, the belt passing over 15 a pulley 61 on the said shaft 62, and the said shaft 62 is provided with double grooved pulleys 63, one at each of its ends. The grooved section of each pulley 63 is connected by belts 65^a with pulleys 65 on the shafts 20 of the forward side paddle wheels as is shown in Fig. 14, and each shaft 40 of the said paddle wheels is provided with a second pulley 66, and these extra pulleys 66 are connected by belts 66^a with pulleys 67 located on the 25 shaft 40 of the foremost and centrally located paddle wheel. The other grooved sections of the pulleys 63 on the line shaft 62 are connected by belts 68 with double-grooved pulleys 69 secured on the shafts 40 of the intermediate side paddle wheels as also shown in 30 Fig. 14, and the other grooved sections of the said pulleys 69 are connected by belts 70 with pulleys 71 secured upon the shafts 40 of the rearmost side paddle wheels, and the 35 shaft of each of these paddle wheels is provided with an auxiliary pulley 72. The said auxiliary pulleys 72 are connected by belts 73 with pulleys 74 secured on the shaft of the central rearmost paddle wheel, as is also 40 shown in Fig. 14. But I desire it to be understood that I do not confine myself to the above described system of driving the paddle wheels, since the line shaft 62 may be omitted and the driving of said paddle wheels 45 may be effected by coupling them directly with the drive shaft of the motor.

It is frequently necessary to balance the vessel, since the force of the wind on one side may be much greater than that on the other. 50 To that end I provide a balancing mechanism, which consists of a shifting pulley E, shown in detail in Fig. 13, which comprises a sheath or body 75, having chambers at its ends, which chambers open at the sides of the frame, and in the upper chamber a friction pulley 76 is mounted to revolve and in the lower chamber a corresponding pulley 77 is mounted. At the central portion of the body or sheath 75 of the pulley E, an aperture 78 is produced through which a bail 79 is passed, which bail is attached to a counterbalancing weight 80. A cable 81 is attached at one end to one member, the right-hand member for example, of the forward diagonal 55 braces 29, as is shown in Figs. 3 and 6, and

this cable is then passed over the lower pulley 77 in the block or sheath E and thence rearward through a guide 82 carried by the left-hand longitudinal brace beam 28 of the keel section a' of the frame. The cable is 70 then continued rearward and is passed over a drum 83, suitably mounted and adapted to be operated by hand or otherwise, and is then returned forward and again passed through the guide 82 and is carried upward 75 and forward and passed over a guide pulley 84 attached to the upper portion of the left-hand forward diagonal brace 29 as is also shown in Fig. 6. From this guide pulley 84 the cable is carried downward and rearward 80 and is passed over the upper pulley 76 in the block or sheath E and is again carried upward and forward, but to the right, and is secured at a point 85 to the right-hand forward terminal brace 29, the last point of attachment 85 being preferably opposite the point of attachment of the aforesaid guide pulley 84. In the operation of this portion of the regulating mechanism for the vessel, if the drum 83 is turned in one direction the 90 block or sheath E will be carried downward and inward toward the center of the vessel and in direction of one side of the vessel, thus carrying the ends of the counterbalancing weight 80 in direction of that side. Should 95 the counterbalancing weight 80 be needed at a point farther from the center of the vessel to produce a proper equilibrium, or at the opposite side of the vessel to restore it to equilibrium, it is simply necessary to turn 100 the drum 83 in an opposite direction, whereupon the sheath E will be carried upward and will be moved in direction of the opposite side of the vessel.

The steering is accomplished through the 105 medium of two rudders, a vertical or perpendicular rudder F and a horizontal rudder F', both of which are particularly shown in Figs. 6 and 7. Both rudders are constructed with light frames and a cloth or fabric body although light metal may be employed as a body. The perpendicular rudder F is secured to a suitable post 86, which is mounted in proper bearings at the stern of the vessel, and the said perpendicular rudder is provided 110 with angular arms 87 at each side, extending rearward from the rudder post. At the rearwardly-extending pointed portions of the said arms the trunnions 89 of the horizontal rudder F' are fulcrumed, the said horizontal rudder F' having a longitudinal central opening 88 therein, so that the horizontal rudder in no manner interferes with the action of the perpendicular rudder F. The horizontal rudder F' may be mounted to have 115 lateral as well as vertical pivotal movement, and the two rudders may be operated by the navigator of the vessel through any well-known means. The object of this construction is to provide a means for moving the 120 125 130

horizontal rudder F' in a vertical direction to obtain a variable angle with the side faces of the perpendicular rudder F without interfering with the action of said rudder F, rendering the joint action of the two rudders particularly effective when turning the perpendicular rudder to the right or to the left, since the horizontal rudder F' may then be placed at any desired angle to the perpendicular rudder and will catch the air at a certain point to the right or to the left of a central longitudinal line drawn through the vessel and the rudder posts, to offer a suitable resistance to the tendency of the vessel to career in turning.

In addition to the two above-mentioned rudders F and F', I provide what may be termed an additional rudder designated as F², but which is in reality a brake rudder.

This brake rudder F² is located below the platform or bottom 26 of the vessel, as shown in Figs. 3 and 7, and when not in use is brought to a horizontal position beneath the said platform, and when carried vertically downward from the platform, or at any desired angle thereto will proportionately serve to retard the progress of the vessel should it be too rapid, or should it be desirable to suddenly stop the vessel. This brake rudder F²

is made of any suitable light material stretched over a proper frame. The frame has trunnions which are mounted usually in blocks 90, extending downward from the lower sills of the vessel as best shown in Fig.

7. Each trunnion is provided with an attached lever 91, terminating at its outer end in a pin projection 92, and these levers 91 are below spaces 91^a, between the platform or bottom proper of the vessel and the lower

side sills as shown in Figs. 3 and 7. Each lever 91 is provided with a handle 93, adapted when the brake lever F² is in a vertical or operative position shown in Fig. 7, to extend up through the said spaces 91^a so that the

handles may be readily grasped, either one or the other, to lift the brake rudder when desired, or to change its angle with reference to the bottom of the vessel. When, however, the brake rudder F² is in its inactive or upper position shown in Figs. 3 and 6, the levers 91 will occupy a vertical position and the brake rudder a horizontal position. The said brake rudder may be held in such position as long as desired by means of hooks 94 carried by the frame, which hooks will then engage the pin projections 92, the latter being in a vertical position as shown in Fig. 6. It will be understood that but one of these hooks is necessary to accomplish the purpose.

Having thus described my invention, I claim as new and desire to secure by Letters Patent,—

1. In aerial vessels, a skeleton frame, hooded paddle wheels mounted in the frame, means for driving the paddle wheels, and sus-

taining devices between the paddle wheels, which receive, temporarily hold and rectify the disturbed currents of air and direct them to the following hoods and paddle wheels, as described.

2. In aerial vessels, a skeleton frame, a series of paddle wheels mounted in the frame, hoods over the paddle wheels, and sustaining devices which receive the currents of air from the paddle wheels, temporarily retain the air and direct it to other paddle wheels and their hoods, as described.

3. In aerial vessels, a skeleton frame, paddle wheels mounted to revolve in the frame, stationary hoods for the paddle wheels, and sustaining devices between the hooded paddle wheels, which sustaining devices serve as receivers and conductors of the currents of air delivered to them by the paddle wheels, as described.

4. In aerial vessels, a skeleton frame, hooded paddle wheels mounted in the frame, means for driving the paddle wheels, sustaining devices located between the paddle wheels to receive the air therefrom, which air is directed to the upper portion of the said retainers, and aeroplanes located above and below the said retainers.

5. In aerial vessels, a skeleton frame, hooded paddle wheels mounted in the frame, substantially diamond-shaped sustainers located between the paddle wheels, receiving air therefrom and compressing said air, the air from the paddle wheels being directed upward within the sustainers, an aeroplane stationarily located beneath each sustainer, and elongated aeroplanes stationarily located above said sustainers, extending down at their outer sides and spaced therefrom, as described.

6. In aerial vessels, a skeleton frame, hooded paddle wheels mounted to revolve in said frame, means for revolving said paddle wheels, stationary, substantially diamond-shaped sustainers located between the paddle wheels, open at the front and at the rear, which sustainers are made in an upper and a lower section, the opposing ends of the sections being contracted, spaces intervening between the opposing ends of the sections, and aeroplanes stationarily located above and below the sustainers.

7. In aerial vessels, a skeleton frame, hooded paddle wheels mounted to revolve in said frame, substantially diamond-shaped sustainers located between the said paddle wheels and receiving the air therefrom and air direct from the atmosphere, which sustainers are open at the front and at the rear, aeroplanes located above and below the sustainers and at the forward and rear portion of the frame, the said frame being also provided at its extreme forward portion with an arched aeroplane and at its extreme rear portion with a flat aeroplane.

8. In aerial vessels, a skeleton frame divided into a series of skeleton cubical compartments, hooded paddle wheels and sustainers in alternate engagement located within the said compartments, the said sustainers being substantially diamond-shaped and open at the front and at the rear and provided with means for admitting air at its side portions, means for driving the paddle wheels, a forward arched aeroplane at the upper forward portion of the frame, a flat aeroplane located at the upper rear portion of the frame, triangular aeroplanes located at the forward and rear portions of the said vessel outside of the line of paddle wheels and sustainers, and flat aeroplanes located one above and the other below each of the sustainers.

9. In aerial vessels, a skeleton frame, a series of vertically alining upper and lower hooded paddle wheels, the hoods having forward and bottom openings only, means for rotating the paddle wheels, and substantially diamond-shaped sustaining devices between said hooded paddle wheels, which sustaining devices present wedge shaped upper, lower and side surfaces, said sustaining devices being open at the front and rear and their front and rear edges being tapered in opposite directions from the top to the central portion of the sides and the bottom to the same points at the sides, all arranged for operation substantially as described.

10. In aerial vessels, a skeleton frame, a series of vertically alining upper and lower hooded paddle wheels, the hoods having forward and bottom openings only, means for rotating the paddle wheels, and substantially diamond-shaped sustaining devices between said hooded paddle wheels, which sustaining devices present wedge-shaped upper, lower and side surfaces, said sustaining devices being open at the front and rear and their front and rear edges being tapered in opposite directions from the top to the central portion of the sides and the bottom to the same points at the sides, all arranged for operation substantially as described, the said sustaining devices being constructed in an upper and a lower section having spaces intervening their opposing ends, and means for rigidly holding the sustaining devices in the said frame.

11. In aerial vessels, an operating medium consisting of a hood closed except at its bottom and forward portions, and a paddle wheel mounted to revolve partially within and partially without the hood, which paddle wheel consists of a triangular hub and triangularly-arranged scoop shaped blades secured to the hub.

12. In aerial vessels, an operating medium consisting of a hood closed except at its bottom and forward portions and a paddle wheel mounted to revolve partially within and partially without the hood, comprising a

shaft, a triangular hub upon the shaft, and blades secured to the corners of the hubs, which blades have substantially concaved under and convexed outer surfaces, as set forth.

13. In aerial vessels, an operating mechanism consisting of a hood closed except at its bottom and forward portions, and a paddle wheel mounted to revolve partially within and partially without the hood, comprising a shaft, a triangular hub upon the shaft, and blades secured to the corners of the hub, which blades are scoop-shaped, having concaved under and convexed outer surfaces, and triangular external skeleton bracings for the wheel, having attachment to the outer longitudinal portions of the blades of the wheel.

14. In aerial vessels, opposing operating devices, each comprising a hood and a paddle wheel mounted to turn partially within and partially without the hood, and a sustaining device located between the operating devices and in communication with both, each of which sustaining devices is substantially diamond-shaped and open at the front and rear, as specified.

15. In aerial vessels, opposing operating devices, each comprising a hood and a paddle wheel mounted to turn partially within and partially without the hood, a sustaining device located between the operating devices, and in communication with both, which sustaining device is substantially diamond-shaped, is stationary and is open at the front and at the rear, whereby to present upper and lower side exterior surfaces, the front and rear edges being inclined inwardly and downwardly from their upper portions to a central line, and inclined upwardly and inwardly from the bottom to the said central line, said sustaining device being also provided with side openings, and means for directing the air from the paddle wheel with force against the upper section of the sustaining device.

16. In aerial vessels, a body frame, a bow and a stern projection from the upper portion of said frame, a flat aeroplane carried by the stern projection and a bowed aeroplane carried by the bow projection, the convexed surface of the said forward aeroplane being uppermost, for the purpose described.

17. In aerial vessels, a body frame, a bow and a stern projection from the upper portion of the said frame, a flat aeroplane carried by the stern projection, and a second aeroplane carried by the bow projection, which latter aeroplane is downwardly arched, said bow aeroplane being triangular in general contour and widest at the rear, the said bow aeroplane also having its front and rear reaches inclined from its center inwardly to its terminal portions, as specified.

18. In aerial vessels, a frame, a rudder post at the rear of said frame, a vertically dis-

posed rudder secured to said post, an auxiliary horizontal rudder slotted to receive the main rudder and pivotally supported thereby, whereby the auxiliary rudder may turn with the main rudder and may be shifted to vary its angularity with respect to the main rudder, for the purposes set forth.

In testimony whereof I have signed my name to this specification in the presence of two subscribing witnesses.

LYCORTES D. MERRICK.
